Fig. 1.

UNITED STATES PATENT OFFICE

2,161,091

CHECK SEPARATOR

David C. Rockola, Chicago, Ill.

Application September 28, 1936, Serial No. 102,916

7 Claims. (CL 194—102)

This invention relates to coin controlled apparatus and to check or coin element separating means particularly adapted for use with coin controls having a reciprocable slide in which 5 is deposited a coin or token for movement by the slide into a suitable receptacle to release a desired mechanism, such as game apparatus or a vending device, for operation.

The invention particularly provides a novel 10 check separator in the form of a pivoted coin receiving pan mounted below a coin discharge aperture of a slide above coin receiving receptacles, and adapted for movement by operation of the slide to pivot relative to the receptacles 15 and variously deposit genuine and spurious coin elements into said receptacles in a manner to be more fully pointed out hereafter.

Additional novel objects in structure and function will appear as the following particular 20 description proceeds in view of the drawing in which:

Fig. 1 is a side elevation of an improved coin control or coin slide mechanism;

Fig. 2 is a bottom plan view of the device of 25 Fig. 1;

Fig. 3 is a vertical longitudinal section, taken along the lines 3—3 of Fig. 2; while

Fig. 4 is a lateral section taken along the lines 30 4—4 of Fig. 1.

The general construction and operation of a 35 type of coin slide with which my novel separating mechanism is particularly adapted to operate, is set forth in United States Patent No. 2,053,503 to Tratsch et al., and issued upon application Serial No. 43,153, filed October 2, 1935.

It is to be understood that the separating mechanism disclosed herein is susceptible of various modifications and adaptations without departing from the scope of the invention, and 40 the particular coin slide mechanism herein described for purposes of illustration is not to be construed as a limitation.

A suitable coin control mechanism with which 45 my improved separating means may be used is shown in Fig. 1 and comprises a main frame member 10 having an integral mounting plate 12 for attachment to the side wall of a cabinet or the like, and a reciprocable coin deposit slide 14 movable in the frame 10. The mechanism is provided with a suitable set of fraud preventing dogs 16, 18 and 20, of types known in the art, these dogs being adapted to ride variously against a coin or token during its movement rearwardly 50 by the slide 14 for purposes of preventing fraudu-

lent operation of the control by the use of apertured and other spurious tokens and coins.

The frame member 10 has at its rearward (left-hand) extremity a depending chambered part 22, in which is a coin receiving aperture 5 or well 24 (Fig. 3) with which a coin receiving aperture 26 is registered when the slide 14 is at the limit of its inward stroke, as shown in Fig. 3, so that a coin carried by the latter will drop into the well 24 under the urging of a 10 presser finger 28 against which the edge of the coin bears during its inward movement.

A bottom surface for the coin chamber 22 is provided with a closure plate 30 attached thereto by means of screws 32, and a second ejecting 15 slide 34 is supported between the closure plate 30 and a longitudinally channeled portion 23 in the undersurface of the housing, for sliding movement in a plane substantially parallel to that of the slide 14. Ejecting plate 34 is also provided 20 with a coin receiving aperture 36 (Fig. 3) which is normally in register with the well 24 in the coin chamber 22, so that a coin having moved into the latter will likewise be urged by the presser finger 28 into the aperture 36 in the 25 ejecting slide and will be prevented from passing downwardly through the latter by the underlying portion of the bottom plate 30.

The ejector slide 34 is provided with a headed post 38 extended outwardly therefrom for engagement with a longitudinal slot 40 in slide 14, such that the slide 14 is permitted a given amount of sliding movement in either direction without effecting any movement of plate 34 until the slide approaches the latter part of its inward stroke, 35 whereupon a shoulder portion (not shown in detail but indicated at 42, Fig. 3) extending toward the middle of the slot or channel 40 will abut the pin 38 and thereafter during the remainder of the inward stroke of slide 14 urge 40 the ejecting slide 34 inwardly to bring the coin aperture 36 therein beyond the edge 44 of the bottom plate 30, and thus permit a coin resting in the aperture to be urged over the edge and into a desired coin receptacle. 45

The ejecting slide 34 is normally urged by a spring 46 toward the right (Figs. 1 and 2) for registration of its aperture 36 with the well 24, into which position it will move upon retraction of the coin slide 14 to its normal outward position. 50

To separate tokens or coin elements of lesser diameter than that of a genuine or authorized coin element, I have provided a separator chute or pan 52 (Fig. 4) 55

in its bottom wall 56, through which a coin of unauthorized diameter is adapted to pass.

The chute 50 has a lower lip portion 58 and a pair of upstanding side walls 60, 61, and is pivoted on a pin 62 which extends through the side walls 60 and 61 and the depending arms 64 of a bracket 66 which is attached to the underside of the ejecting slide 34.

The rearward (left-hand) upper extremity of 10 the chute or pan 50 has a notched portion 68 formed by upsetting a portion of the material thereof to provide the rear end wall or abutment 69 (Fig. 3) adjacent the pin 62, and a coil spring 70 on the pin has an end portion 72 extended through the cut-away part 68 to bear 15 against the underside of the slide 34, while the opposite extremity 74 of the spring extends downwardly through the slot or cut-away port 68 to underlie the bottom side of the pan and bear against 20 the latter, so that the coil spring may be tensioned when the chute is pivoted downwardly.

The side wall 61 has an outwardly extended 25 ear 76 which is curved on its horizontal surface to form a cam edge for engagement with a corresponding cam edge 78 of a depending cam plate generally indicated at 77. This cam plate is of substantially triangular shape and has an angled bracket extension 79 through which extends an attaching means such as screws 32', to 30 secure it to the bottom wall of the coin chamber 22 (Fig. 4).

The chute 50 is normally in the position shown in Fig. 1; that is to say, pivoted into a downward discharging position in such manner that 35 the lip portion 58 thereof will be disposed above the mouth of a coin receptacle 59.

Operation

Assuming the parts to be as shown in Fig. 1, 40 it will be observed that the separator chute 50 is positioned in a downwardly inclining direction above the coin receptacle 59 against the tensioning of its coil spring 70, because the outwardly extending cam ear 76 is urged against the cam 45 edge 78 of the depending cam plate 77, since the discharging or ejecting slide 34 on which the chute 50 is pivoted, is urged inwardly by the spring 46.

At this time a coin may be deposited in the 50 coin receiving aperture of the slide 14 and the latter may be urged inwardly into the full stroke position shown in Fig. 3. As soon as the shouldered part indicated at 42 of the longitudinal channel or slot 40 in the slide 14 engages the 55 upstanding pin 38 on the ejecting slide 34, the latter will be carried inwardly with the slide 14 against the tension of the spring 46 and carry the ejecting chute or pan 50 rearwardly so as to move the cam ear 76 away from the cam edge 60 78 of plate 77, thus permitting the pan to rise into a substantially horizontal position under the urging of its spring 70 as shown in Fig. 3.

At this time any coin previously deposited and lying in the coin aperture 36 of the discharge or 65 ejecting slide 34, will be positioned above the apertured part 52 of the pan 50 and the coin or token will drop into the pan, and if it is of a proper size remain therein until the coin slide 14 is retracted. However, if the coin is less than 70 a predetermined size, it will drop through the aperture 52 in the pan and pass into any suitable receptacle 57 over which the pan will be positioned, by the inward movement of the slide 14. Assuming, however, that the coin thus 75 deposited into the raised chute or pan 50 is of

proper size, it will not, of course, drop through the aperture 52, but upon the return of the slide 14 to its normal outward position the discharging or ejecting slide 34 will be urged back into its normal position (left to right in Fig. 1) by the 5 spring 46 as soon as the shouldered portion 42, in the longitudinal channel or slot of slide 14, is withdrawn from abutment against the post 38.

This latter return movement of the auxiliary or discharging slide 34 will again cause the cam 10 ear 76 on side wall 61 of the chute 50 to bear against the cam edge 78 of the depending cam plate 77, and as the discharge slide reaches the limit of its right-hand movement toward normal position the chute will be pivoted against the 15 tension of its spring 70 downwardly so as to bring the discharge end or lip 58 thereof above the coin receptacle 59, whereupon the coin previously resting in the pan or chute will gravitate 20 into the receptacle.

While it has been pointed out herein that the particular coin slide mentioned for purposes of illustration is provided with selecting dogs operable variably to prevent fraudulent actuation of the slide by use of spurious coins including 25 those of less than a predetermined diameter, it is thought desirable to mention further that slides such as the one mentioned are arranged to operate when a token of slightly less diameter than a genuine coin, such as a nickel, is deposited 30 therein, the reason for this being that it is unlawful to use a token which simulates a genuine coin identically in dimension. Therefore, tokens are employed which have a diameter very slightly less than the diameter of a genuine coin, and the selecting dogs on the coin slide will permit 35 such tokens to pass although these dogs would function to prevent the operation of the slide upon deposit of a coin or token of appreciably less diameter than the aforementioned nickel coin 40 or token which is intended to be substituted for the nickel. To illustrate, the coin slide described herein may be operated by deposit of a genuine U. S. nickel coin; this slide may also be 45 operated by a token having a diameter perhaps 5/1000 under the diameter of the nickel, for example; however if a penny were inserted in the slide the dogs would prevent its operation. One of the useful functions of the selecting chute disclosed herein is to permit the slightly undersized tokens which operate the slide to pass through the discharge opening in the pivoted chute, while the five-cent pieces are retained in the chute and discharged when the same is pivoted in the manner set forth.

The embodiment of the invention shown herein for purposes of illustration is not to be understood as confined to the precise details set forth, but is to be limited only to such details of structure and function as may be fairly within the 60 scope of the appended claims.

I claim:

1. In a coin separator, a coin slide structure comprising means for receiving and discharging a token or coin therefrom, a pair of coin receiving means, a chute pivotally mounted beneath said structure and provided with an aperture therein disposed in the path of coins discharged from said slide structure and of a size to enable tokens or coins of less than predetermined size 70 to pass therethrough into one of said receiving means, means for holding said chute substantially horizontal while in coin receiving position, and means for tilting said chute for effecting the 75 gravitational discharge from the free end thereof 75

into said other receiving means of a token or coin deposited by said structure in said chute of a size incapable of passing through said aperture.

2. In a coin separator, a coin slide structure comprising a guide and upper and lower apertured coin slides adapted to be reciprocated to and from coin depositing position, a pair of coin receiving means, said guide having an aperture adapted to register with the apertures of said upper and lower slides during the movement of said slides inwardly for effecting the transfer of a coin therethrough, a coin chute pivotally secured adjacent one end thereof to said lower slide and reciprocable therewith and provided with a spring 10 tending to retain the same in substantially horizontal position, said chute having an aperture therein in registration with the aperture of said lower slide through which may pass from said slide into one of said receiving means coins or tokens of less than a given size, and cam means 15 cooperating with said chute for swinging the free end of the same downwardly against the action of the spring thereof during the final portion of the return movement of said chute for effecting 20 the gravitational discharge therefrom into said other receiving means of a token or coin of a size incapable of passing through the aperture thereof.

3. In a coin separator, a coin slide structure, a pair of coin receiving means, a coin chute pivotally mounted adjacent one end beneath said structure and provided with an aperture through which deposited checks or coins of less than a given size may pass into one of said receiving means, means for holding said chute substantially horizontal when in coin receiving position, said structure comprising operatively connected reciprocable upper and lower apertured slides and a guide frame having a passage adapted to register with the passages of each slide during inward 30 movement thereof to effect the transfer of a coin from the upper slide into said chute, said chute being connected to and movable with said lower slide, and cam means for swinging the free end of said chute downwardly during the return movement of said lower slide for effecting the discharge into said other receiver of a deposited check or coin of a size incapable of passing through the aperture of said chute.

4. In a coin separator, a coin slide structure, a pair of coin receiving means, a coin chute pivotally mounted adjacent one end beneath said structure and provided with an aperture through which deposited checks or coins of less than a given size may pass into one of said receiving means, means for holding said chute substantially horizontal when in coin receiving position, said structure comprising operatively connected reciprocable upper and lower apertured slides and a guide frame having a passage adapted to register with the passages of each slide during inward movement thereof to effect the transfer of a coin from the upper slide into said chute, said chute being connected to and movable with said lower slide, and means comprising a stationary 40 cam and a cooperating cam follower carried by said chute for swinging the free end of the same downwardly during the return movement of said

lower slide for effecting the discharge from the chute into said other receiving means of a deposited check or coin of a size incapable of passing through the aperture of the chute.

5. In a coin separator, a coin slide structure, a pivotally mounted chute therebeneath, a pair of coin receiving means, means for holding said chute substantially horizontal when in coin receiving position, said structure comprising cooperating reciprocable slide means and a frame 5 having passages therein adapted to register during a portion of the inward movement of said means to effect discharge of a coin from said means to said chute, said chute having an aperture intermediate the ends thereof for the passage therethrough into one of said receiving means of coins of less than a predetermined size, and means for swinging said chute pivotally to lower the free end thereof during a subsequent portion of the movement of said slide means for causing a coin in said chute of a size incapable of passing through said aperture to be discharged from the free end of the chute into said other receiving means.

6. In a coin separator, a coin slide structure, a chute pivotally mounted beneath said structure, a pair of coin receiving means, means for holding said chute substantially horizontal when in coin receiving position, said structure comprising a guide frame and upper and lower operatively connected reciprocable slides provided with cooperating passages adapted to effect the transfer of a coin from the upper slide into said chute during the inward movement of said slides, said chute being secured to and movable with said lower slide and having an aperture therein intermediate the ends thereof for passage therethrough into one of said receiving means of a transferred coin of less than a predetermined size, and means coacting with said lower slide during 35 the return movement of the same for effecting the downward tilting of the free end of said chute for discharging thereover into said other receiving means a deposited coin of a size incapable of passing through said aperture.

7. The combination with a coin slide structure provided with passages adapted to register during reciprocating operation thereof to enable a token or coin to drop therethrough, of a pair of coin receiving means, a token or coin receiving chute pivotally mounted adjacent one end beneath and to said structure and reciprocally movable thereby and provided with an aperture aligned with the path of such dropped coins through which tokens or coins only of less than a predetermined 50 size may pass into one of said receiving means, a spring tending to retain said chute in substantially horizontal position for the retention therein of deposited tokens or coins above a predetermined size, and cam means engageable with said chute during a final portion of each operation thereof for deflecting the free end of the same downwardly to cause a token or coin therein to be discharged therefrom by gravity into said other receiving means.

DAVID C. ROCKOLA.
